US00D747984S

(12) **United States Design Patent**
Zhao et al.

(10) **Patent No.:** US D747,984 S
(45) **Date of Patent:** ** Jan. 26, 2016

(54) **BLUETOOTH-BASED SENSOR**

(71) Applicants: **Wuyang Zhao**, Beijing (CN); **Ruojiao Zhang**, Beijing (CN); **Xin Zheng**, Beijing (CN); **Xiaofei Yuan**, Beijing (CN); **Mingming Zhang**, Beijing (CN)

(72) Inventors: **Wuyang Zhao**, Beijing (CN); **Ruojiao Zhang**, Beijing (CN); **Xin Zheng**, Beijing (CN); **Xiaofei Yuan**, Beijing (CN); **Mingming Zhang**, Beijing (CN)

(73) Assignees: **Sensoro Co. Ltd.**, Beijing (CN); **Wuyang Zhao**, Biejing (CN); **Donhwei Zhao**, Beijing (CN)

(**) Term: **14 Years**

(21) Appl. No.: **29/501,061**

(22) Filed: **Aug. 30, 2014**

(30) **Foreign Application Priority Data**

Jul. 31, 2014 (CN) 2014 3 0266409

(57) **CLAIM**

The ornamental design for a bluetooth-based sensor, as shown and described.

DESCRIPTION

FIG. 1 is a perspective view of the bluetooth-based sensor showing my new design;

FIG. 2 is a front elevational view thereof;

FIG. 3 is a rear elevational view thereof;

FIG. 4 is a left side elevational view thereof;

FIG. 5 is a right side elevational thereof;

FIG. 6 is a top plan view thereof; and,

FIG. 7 is a bottom plan view thereof.

The dashed lines are intended for the purpose of illustrating environment and form no part of the claimed design.

1 Claim, 7 Drawing Sheets

FIG. 1

FIG. 2

FIG. 3

FIG. 4

FIG. 5

FIG. 6

FIG. 7
